UNITED STATES PATENT OFFICE.

GEORGE HOVEY KENDALL, OF NEW YORK, N. Y.

PLATE-PRINTING MACHINE.

No. 823,878.

Specification of Letters Patent.

Patented June 19, 1906.

Application filed December 9, 1905. Serial No. 291,030.

To all whom it may concern:

Be it known that I, GEORGE HOVEY KENDALL, a citizen of the United States, residing at the city of New York, in the borough of Manhattan and State of New York, have invented certain new and useful Improvements in Plate-Printing Machines, of which the following is a full, clear, and exact description.

My invention relates to traveling-bed-plate machines.

The purpose of the invention is to provide a machine of this character which shall be compact and efficient and which shall be capable of turning out the highest grade of plate-printing work, such as bank-notes, treasury-certificates, bonds, securities, and the like.

With these and other objects in view my invention consists in the construction, combination, location, and arrangement of parts, all as will be more fully hereinafter described, as shown in the accompanying drawings, and finally particularly pointed out in the appended claims.

In the drawings, Figure 1 is a side elevation of the complete machine. Fig. 2 is a detail plan view of the bed. Fig. 3 is a detail side elevation of the impression-cylinder. Fig. 4 is an end view of the same. Fig. 5 is a sectional view showing the impression-cylinder and a portion of the bed. Fig. 6 is a side elevation of the machine from the opposite direction to that of Fig. 1, and Fig. 7 is a section on the line 7-7 of Fig. 6 looking in the direction of the arrows.

Plate-printing as now performed is a very difficult and expensive operation. The plate must be carefully inked and then wiped off with a cloth which must have a surface suitable for the work, and afterward the surface must be polished. The plate is then run through the press in contact with the surface to be printed and under heavy pressure. All of this is now commonly done on a form of hand-press in which the operator wipes the plate by hand and subsequently rolls it through the machine by means of a large hand-wheel. While power-presses have been used, they have not been successful up to the present time on account of the too mechanical nature of their operation. It seems to be necessary to have a machine of great precision and simplicity which shall be so strongly built as to avoid vibration and which shall as closely as possible imitate hand-work in order to secure the best results.

Referring now to the drawings and to the various views and reference-signs appearing thereon, in which like parts are designated by the same reference-sign wherever they occur, 60 1 indicates the frame of a plate-printing machine embodying the principles of my invention. Suitably journaled within this frame is the main power-shaft 2, which is conveniently driven by pulley 3 and belt 4 from an 65 electric motor 5 or any other suitable means. I have shown the power-shaft 2 geared to a main operating-shaft 6 by intermediate pinions and gears 7, 8, 9, and 10. In this way the operating shaft 6 is caused to rotate at a 70 comparatively slow speed and in a right-handed direction in Fig. 1 of the drawings. All the moving parts of my machine are operated more or less directly from this main operating-shaft 6, and I regard this as an important feature of my invention. By this means perfect synchronism of the parts is attained and a simple and rigid construction provided which is a most essential requisite of mechanical plate-machines. The printing- 75 couple is driven from the operating-shaft 6 through a crank 11 and pitman 12, connected at 13 to the rocking-lever 14, which is pivoted at 15 to the main frame of the machine. 16 denotes the bed of the machine, which is 80 guided to reciprocate to and fro upon the machine and is impelled in such movement by a link 17, extending to the upper end of the rocking lever 14, above described.

I provide a practical construction for binding and supporting the bed comprising side guides 16², arranged to overhang and position the bed in its sliding movement, and a bearing-roller 16³, journaled in the frame at 16⁴, which serves to support the bed directly beneath the line of printing-contact. I prefer to gear this roller directly to the bed by means of gear 16⁵, meshing with rack 16⁶ upon the under side of the bed.

In order to secure an inspection of the 100 wiped plate, I form the bed 16 in a special way, having a prolonged extension 18 at its forward end. Upon this extension and extending throughout the length of the bed I secure the rack 19, meshing with the gear 20 105 upon the impression-cylinder 21. This impression-cylinder is journaled in vertically-sliding bearings 22 upon the main frame of the machine so as to be oscillated to and fro by the rack 19 whenever the bed 16 is reciprocated in the manner above described. 110 By virtue of the arrangement of the rack 19

on the extension 18 it will be seen that the effective printing portion of the bed, which corresponds to the central portion of the throw thereof, or, in other words, the central portion of the rack 19, is quite near the free end of the bed, as will be seen in Fig. 2. As the operating-shaft 6 rotates the bed 16 is reciprocated back and forth beneath the impression-cylinder 21, which latter is oscillated thereby, so as to produce a perfect rolling contact between the two surfaces of the printing-couple.

23 indicates the engraved, etched, or otherwise-prepared plate, which is secured to the bed 16 at a point substantially opposite the central portion of the throw thereof, which corresponds to a location somewhere near its free end, as shown in Fig. 2 and as above described. In this way the plate is in convenient reach of the operator, who stands near the right-hand end of the machine, in Fig. 1, to exercise a general surveillance of its operations. In its reciprocation the plate passes from this position in front of the operator first under the impression-cylinder 21 and subsequently under certain inking and wiping devices which will be later described, and thence again under the impression-cylinder. I employ any ordinary form of throw-off in carrying out my invention which raises the impression-cylinder 21 away from the bed upon such return or forward stroke.

A convenient form of throw-off mechanism is illustrated in Figs. 1 and 7, comprising a heavy rock-shaft 24, having downwardly-projecting cranks, (shown at 25,) to which are secured the links 26, which draw downward the impression-cylinder in vertical guides 27. 28 shows in dotted lines a spring-pressed link which constantly tends to throw the cranks 25 to the left, so as to draw downward the impression-cylinder. The rotation of the operating-shaft 6 is effective to bring a cam 29 periodically into contact with the roller 30 upon one of the cranks 25, which positively raises the impression-cylinder upon every forward stroke of the bed 16. I also connect a handle to the shaft 24 for throwing off the impression-cylinder whenever desired, the details of which are particularly illustrated in Fig. 6. 30² indicates the hand-lever pivoted to the frame of the machine at 30³ and having a link 30⁴ extending to a rocking bell-crank lever 30⁵. The toe 30⁶ of this lever may be rocked into position to intercept the movement of the cranks 25 as they swing downward under the influence of spring-rod 28, before mentioned, thereby preventing an impression whenever the throw-off lever 30² is moved backward by the operator.

At a point behind the impression-cylinder I provide inking mechanism for the plate, 65 and this may be of any suitable or desired

construction. In the drawings I have indicated an ink-reservoir 31 in contact with a roller 32, which is turned at intervals through a varying degree by a crank 33 and pitman connection 34 from the main operating-shaft 6. 35 indicates a ductor-roller which oscillates back and forth by means of cranks 36 and a reciprocating rod 37, driven by a cam 38 upon the pivot-shaft 15, above described. 39 indicates an ink-carrying roll 75 which is positively geared through an idler 40 to the inking-roller proper, 41, which is in turn geared to the rac 42 upon the bed 16, which is conveniently extended beyond the bed to the left, as at 42', so as to always remain in mesh with idler 40. By this means the inking-roller 39 is given a peripheral speed always equal to the speed of movement of the bed and rolls over the printing-plate without friction when in contact therewith. I do not regard the features of this inking mechanism as novel with me; but it is necessary to explain this construction in order that the action of the wipers later described may be made clear.

The wiping mechanism embodies a pair of pads 43, which extend transversely across the machine and are supported at their ends by rocking cranks 44, journaled at 45 and reciprocated from a pitman 46, and crank 47, 95 driven by a beveled gear 48 from the power-shaft 2. I lead over the surface of these pads 43 a fabric, preferably of canton-flannel, and I employ a method of utilizing this fabric, which I believe to be novel, with the present invention. Instead of feeding the fabric continuously a small amount at each printing operation, I secure the wiping-cloth in absolutely stationary relation upon the pads, in which position it successively wipes over the plate and prepares the same for printing. By this method the wiping-surface acquires characteristics entirely different from those of a wiper which is continuously or intermittently fed. A wiper which is continuously fed presents to the plate a strip of new clean surface at each printing operation which is rough and fibrous and of a character likely to injure the plate and preclude an efficient wiping operation. With my invention I start with a perfectly clean wiping-surface, which does not give the best results for a number of impressions; but after a few printing operations it becomes covered with a thin coating of ink which serves to cement down the projecting fibers and give the cloth a smooth leathery finish, which is analogous to the condition of the human hand. The small amount of ink which the cloth has upon its surface is not sufficient to leave ink 120 upon the polished parts of the plate, but continues to adhere to the cloth by reason of the more fibrous nature of the latter. On the other hand, by virtue of the smoother wiping-surface, the ink is left in the finest 130

crevices of the plate in the same manner as it is left by the action of the hand in polishing. It will be understood that after the cloth has once attained a proper condition the supply of ink fed from the reservoir 31 may be very much cut down and only a very small quantity of ink used, which is properly distributed over the printing-plate by the wipers and not scraped off and carried uselessly away, as in the present system. After a certain length of time the wipers of course become so much inked that the surface will have to be changed; but the cloth remains in condition for perfect operation for quite a long time and often long enough to obtain many thousand impressions. This method of printing, it will be observed, is economical in both wiping-cloth and ink; but these are not the main objects, the main purpose being to secure perfect printing results equal, if not superior, to those now obtained by the hand process.

49 indicates the fabric which constitutes my wiper, and I lead this fabric from a supply-roll 50 to a take-up roll 51. Each of these rolls has means by which it can be stepped around whenever desired, and I have shown for this purpose ratchet-wheels 52 and 53, upon which act pawl-carrying levers 54 and 55, each having a handle which can be oscillated to turn the rolls. It will be apparent that whenever the wiping-surface becomes unsuitable for further use on account of being fouled by too much ink, the operator merely manipulates the handles 54 and 55 to draw around an entirely new surface of the wiping-cloth.

The printing operation in its essential characteristics will now be understood. The paper is carried by the impression-cylinder and the plate 23 is initially located in front of the operator and at the extreme right-hand end of the machine in Fig. 1. The bed moves to the left, carrying the printing-plate under the impression-cylinder and making the impression, after which the inking-roller 41 comes into action to supply a uniform layer of the ink over the surface of the plate. The bed now commences its return movement, in which the plate is first drawn beneath the wipers 43, which remove the ink from the polished parts in the manner above described. In this action they are assisted by their peculiar oscillating or rocking movement, which somewhat imitates the motion of the hand in wiping. After the pads 43 the plate continues to pass forward beneath the impression-cylinder (which is raised at this time) to the extreme right-hand position in front of the operator. In this position the operator may inspect the plate and see that it is in proper condition and pass his hand over the same to wipe it more perfectly, if he desires, although this is not absolutely essential. It is customary, however, for the op-

erator to do this, since he has no other occupation at this moment, and in some cases a plate is not properly wiped by the automatic wipers by reason of the accumulation of too much ink on the pads 43, or other reason. In any case as a result of the efficient wiping of the pads 43 and the inspection of the operator, together with such hand-wiping as he may make, the plate finally passes forward beneath the impression-surface in perfect condition, where it impresses against the paper in the usual way.

I will now describe briefly the features of the impression-cylinder by which it holds and carries the paper to be printed. I am aware that these features are not broadly new in this machine; but I regard the various front-stop and gripper-operating means as a part of the invention in the manner they are organized into the present machine.

Referring particularly to Figs. 4 and 5 of the drawings, 60 denotes a gripper-carrying shaft pivoted in the ends of the impression-cylinder 21 and carrying gripper-fingers 61, arranged to bear against a portion of the cylinder and grip the paper thereagainst. 62 designates a rock-arm upon the gripper-carrying shaft 60, which is normally spring-pressed in a direction to close the grippers upon the cylinder by a spring 63. 64 indicates a cam-arm which may be rocked into the path of the cam of the rock-arm 62, so as to move the latter against its spring 63 and raise the grippers away from the cylinder. For this purpose the cam-arm 64 is carried by a shaft 65, which can be oscillated from a rod 66, extending into proximity to the main operating-shaft 6. Also extending into proximity to the operating-shaft 6 is a second rod connection 67, which works the usual front stop 68. Both of the rods 66 and 67 are guided by an extension 69 from the frame and carry cam-rollers 70 and 71 at their lower ends. Upon the face of the gear 10, previously described, I arrange cam projections 72, 73, and 74. The roller 70 is in the path of movement of the projections 72 and 73, so that as the main operating-shaft 6 rotates the rod 66 will be raised and the gripper-fingers opened two times during each cycle of operations of the machine. This movement of the gripper-fingers corresponds to the action of grasping and releasing the sheet, respectively. The roller 71 is in the path of the projection 74, which is so located as to depress the front stops 68 in proper relation to the movement of the grippers. I also provide stripper-fingers for withdrawing the printed sheet from the impression-cylinder, as particularly illustrated in Figs. 4 and 5.

75 indicates a row of stripper-fingers mounted on a rock-shaft 76, which is oscillated at certain times by a rod connection 77. The rod 77 is guided to move vertically and has at its bottom end a bearing portion 78,

which is designed to be engaged by a cam or wedge 79 upon the bed. The arrangement is such that as the bed moves to the right the rod 77 is eventually depressed and the fingers 75 thrown away from the impression-cylinder, in which position they remain during the first part of the return stroke, when the impression-cylinder is taking a sheet of paper from the feed-board. When, however, the cylinder has progressed a portion of a revolution, the rod 78 is engaged by the cam-wedge 79 and the stripper-fingers 75 thrown against the impression-cylinder, so that the paper is stripped off of the cylinder and fed into the hands of the operator, who is in a position to receive it. At the instant the paper is about to be stripped from the cylinder by the stripper-fingers 75 the gripper-fingers 61 are of course released by the cam 72, and the sheet 20 is simultaneously deflected away from the cylinder by certain additional lifter-fingers 80. The fingers 80 are supported on a rock-shaft 81 upon the cylinder, which has a cam-arm 82 thereon extending peripherally for a 25 portion of the cylinder.

83 indicates a rock-arm, which is mounted adjacent to the cylinder and adapted to be depressed under certain conditions by a rod 85, bearer 88, and cam-wedge 89, similar to 30 the parts 77, 78, and 79, above described. The parts are so timed that the arm 83 is rocked into engagement with the cam-arm 82 and raises the deflector-fingers 90 at the instant when the grippers release and the stripper-fingers are about to operate. In this 35 way by the release of the grippers and the action of the lifter-fingers 80 the sheet is positively deflected onto the stripper-fingers and delivered from the machine.

40 The operation of my invention will be understood from the preceding description. A feeding assistant stands ordinarily at one side of the machine with a pile of sheets upon the feed-board 59. These are successively 45 placed in a position opposite the front stop 68, whereby they are automatically grasped by the impression-cylinder and carried around into contact with the advancing bed and plate. From thence they are stripped off by 50 the stripper-fingers 75 and pass into the hands of the feeding assistant who is on the lookout to receive them. In the meantime the bed has continued its motion toward the left and carried the plate beneath the inking- 55 roller 41 and subsequently under the wiper-pads 43 and thence beneath the impression-cylinder (which is thrown off at this time) into a position where it is inspected by the operator and where it is again ready to make 60 an impression on the next sheet fed.

A practical feature of my machine relates to the manner in which its motion may be arrested at any time in case a sheet is improperly fed. The operation of the throw-off under these circumstances has been described;

but the throw-off lever is ordinarily only operable by the feeding assistant and is, furthermore, not sufficiently effective to prevent damage to the machine or printing-plate in case a crumpled sheet is moving toward the printing-point. I therefore provide within easy reach of the operator a foot-pedal 86, which has a very powerful brake-shoe 87 thereon adjacent to the periphery of the main drive-wheel 3. Inasmuch as this 75 drive-wheel is geared by reduction-gearing to the operating-shaft 6 the braking-pressure upon it is very effective to instantly arrest the motion of the machine. The driving-motor is of course provided with an ordinary 80 form of magnetic cut-out, so that the motor is automatically stopped by reason of the increased power imposed simultaneously with the action of the brake. Thus the power is shut off and the machine instantly arrested 85 at any time desired by the mere depression of the pedals 86 by the foot of the operator.

What I claim is—

1. In a plate-printing machine, a main power-shaft, an operating-shaft geared to 90 said main power-shaft, a bed carrying a rack connected to be reciprocated by said main power-shaft, an impression-cylinder geared to said rack, front stops and gripper-fingers, link connections from said front stops and 95 additional link connections arranged to operate said gripper-fingers extending in proximity to said main operating-shaft, and means on said operating-shaft for impinging against said links to operate said parts, said means 100 being so timed as to cause a sheet to be received and delivered upon rearward movements of said bed, whereby an impression is made by the printing-plate after it has been inspected by the operator. 105

2. In a plate-printing machine, a bed carrying a rack and having its end cut away adjacent to such rack, whereby an opening is left for the operator to stand and inspect the plate, an impression-cylinder geared to said 110 rack, and inking means and wipers on each side of said impression-cylinder from that where the operator stands.

3. In a plate-printing machine, a bed having a rack and a cut-away portion at one end 115 adjacent to said rack whereby an opening is left for the operator to stand and inspect the plate, an impression-cylinder geared to said rack, inking means and wipers in the rear of said impression-cylinder, and means for moving said bed to initially present the plate for inspection by the operator and subsequently pass it beneath the impression-cylinder and inking and wiping means. 120

4. In a plate-printing machine, a reciprocating bed having an extension at its forward end, a rack upon said bed projecting over said extension, an impression-cylinder geared to said rack, a printing-plate upon 125 said bed in proximity to said forward end of 130

the bed, and inking and wiping means, whereby the same may pass from a position in front of the operator successively under the impression-cylinder and under the inking and wiping means.

5. In a plate-printing machine, a main frame having an operating-shaft, a pitman connection therefrom, a bed guided by said frame to have a fixed movement from said pitman, a rack on said bed and projecting beyond the forward end thereof, an impression-cylinder in mesh with said rack, an additional rack on the bed projecting beyond the rear end thereof, a bearing-roller having a gear in mesh with said rack, and a printing-plate at one end of said bed, whereby the same is initially in position to be inspected by the operator, and then successively passes under the impression-cylinder and under inking and wiping means.

6. In a plate-printing machine, a frame having a main operating-shaft, a bed guided to reciprocate in said frame, a pitman connection from said operating-shaft to said bed, a rack upon said bed and projecting beyond the forward end thereof, an impression-cylinder geared to said rack at substantially the central portion of its throw, an additional rack projecting beyond the rear end of the bed, a bearing-roller having a gear in mesh with said rack, and a printing-plate in proximity to the end of said bed, whereby it successively passes under said impression-cylinder and under inking and wiping means.

35. 7. In a plate-printing machine, a frame having a main operating-shaft, a bed guided to reciprocate in said frame, a pitman connection from said operating-shaft to said bed, and a cut-away portion on said bed adjacent to the printing-plate, whereby the operator may inspect the work prior to its passage under the impression-cylinder.

8. In a plate-printing machine, a frame having a reciprocating bed, an impression-cylinder geared thereto, inking and wiping means at one side of said impression-cylinder, a feed-board at the same side of said impression-cylinder, and a cut-away portion on said bed whereby a clear space is provided 45 for the operator to inspect the work.

50. 9. In a plate-printing machine, a reciprocating bed having a rack projecting forwardly therefrom at its forward end, an impression-cylinder in gear with said rack, a second rack upon the bed projecting beyond the bed 55 at its rear end, inking mechanism in gear with said last-named rack, and wiping means

intermediate said impression-cylinder and inking mechanism whereby the operator may stand in a position to wipe the plate regardless of the movements of the bed.

10. In a plate-printing machine, a reciprocating bed having a plate thereon, an impression-cylinder journaled above said plate and arranged to contact therewith upon the 60 rearward stroke of the bed, stripper-fingers adjacent to said impression-cylinder, and cam-surfaces fixed upon said bed and movable therewith for throwing said stripper-fingers into operative relation as the bed completes its rearward movement.

11. In a plate-printing machine, a reciprocating bed having a printing-plate thereon, an impression-cylinder above said bed, stripper-fingers adjacent to the upper peripheral 75 surface of said cylinder, lifter-fingers upon said cylinder, and cam means upon said bed for operating said stripper and lifter fingers.

12. In a plate-printing machine, a reciprocating bed having a printing-plate thereon near its forward end, an impression-cylinder journaled slightly forward of the mean position of the throw of said plate, stripper and lifter fingers in operative relation to said impression-cylinder, and a pair of cam-surfaces 85 upon the bed for operating said stripper and lifter fingers as the bed completes its rearward movement.

13. In a plate-printing machine, a reciprocating bed having a printing-plate thereon, 90 an impression-cylinder journaled above said plate, stripper-fingers operatively related to said impression-cylinder, a cam-wedge surface upon said bed for lowering said stripper-fingers, lifter-fingers upon the impression-95 cylinder, and a comparatively short cam-wedge for operating said lifter-fingers when the stripper-fingers are lowered.

14. In a plate-printing machine, a main power-shaft, a central operating-shaft geared 100 to said main power-shaft by reduction-gearing, a bed, means for reciprocating said bed from said operating-shaft, an impression-cylinder, front stops and gripper-fingers operatively related to said impression-cylinder, 105 and cams upon said operating-shaft for actuating said front stops and grippers as the bed moves rearward.

In witness whereof I subscribe my signature in the presence of two witnesses.

GEORGE HOVEY KENDALL.
